(57) **CLAIM**

The ornamental design for a double glass door smoker, as shown and described.

DESCRIPTION

FIG. 1 is a top, right front perspective view of a smoker showing my new design;

FIG. 2 is a front elevational view thereof;

FIG. 3 is a left side elevational view thereof;

FIG. 4 is a right side elevational view thereof; and,

FIG. 5 is a top plan view thereof.

The Broken lines included in the drawings depict elements that are not part of the claimed design. The bottom and rear surfaces of the double glass door smoker, not shown, form no part of the claimed design.
